UNITED STATES PATENT OFFICE.

JAMES BOOTH, OF EAST LIVERPOOL, OHIO, ASSIGNOR OF ONE-HALF TO
J. F. H. WARK, OF JOPLIN, MISSOURI.

RAIL-JOINT.

SPECIFICATION forming part of Letters Patent No. 743,437, dated November 10, 1903.

Application filed April 2, 1903. Serial No. 150,798. (No model.)

To all whom it may concern:

Be it known that I, JAMES BOOTH, a citizen of the United States, residing at East Liverpool, in the county of Columbiana and State 5 of Ohio, have invented certain new and useful improvements in Rail-Joints, of which the following is a specification.

This invention relates to improvements in United States Patent No. 672,870, dated April 10, 1901, granted to me for rail-joint, and aims to remedy certain defects in the structure of said joint, and the form of which will be more clearly set forth hereinafter.

For a full description of the invention and 15 the merits thereof and also to acquire a knowledge of the details of construction of the means for effecting the result reference is to be had to the following description and drawings hereto attached.

20 While the essential and characteristic features of the invention are susceptible of modification, still the preferred embodiment of the invention is illustrated in the accompanying drawings, in which—

25 Figure 1 is a perspective view of the joint in operative position. Fig. 2 is a sectional view on the line X X of Fig. 1. Fig. 3 is a perspective view of the bearing-plate. Fig. 4 is a combination view of the end portions 30 of the rail-chair and one fish-plate, parts being broken away, showing more particularly the form of the notched parts.

Corresponding and like parts are referred to in the following description and indicated 35 in all the views of the drawings by the same reference characters.

The main structural parts of the invention are of the same form as has been shown and described in my former patent. These essential 40 elements consist of a rail-chair 1, fish-plates 2, and locking-wedges 3 and 4. The chair 1 is formed with longitudinal flanges 5, and the fish-plates 2 are provided with corresponding longitudinal extensions 6, which are 45 adapted to overlap the flanges 5 of the rail-chair, the said flanges 5 being disposed between the extensions 6 and the bodies of the fish-plates. The extensions 6 and flanges 5 are provided with notches 7 and 8, respectively, 50 the said notches being used to receive locking-wedges 3 and 4 upon one side of the rail

and those disposed upon the other side of the rail to receive pins 9. In order to hold the locking-wedges 4 and the pins 9 in their proper positions, openings 10 are provided at 55 the lower ends of the said pins and wedges, through which are disposed transverse locking-pins 11. These pins prevent displacement of the aforesaid members, and it is not desired to restrict the invention to the use of 60 any special character of locking-pins, but those structurally efficient may be utilized as found convenient. The wedges 3 and the pins 9 are provided with heads 4^a and 9^a, respectively, for obvious reasons. 65

In the practical use of the joint as shown in my former patent it was found that owing to the fact that no locking means were provided to hold the fish-plates upon one side of the rail in their position in the chair 1, due 70 to vibration and analogous causes, these fish-plates will become displaced, and so in this invention the locking means 9 are applied and movement of the fish-plates is obviated. Furthermore, it has been found that due to 75 wear and constant vibration of the rails within the chair the space between the fish-plates and the sides of the chair is enlarged as the period of use of the joint continues and that for this reason the parts become loose and 80 the efficiency of the joint to some extent decreased. For the purpose of providing against this defect in my former joint I have adopted and now use a bearing-plate 12 of 85 peculiar construction and which prevents the rattling and looseness of the parts mentioned, which plate is disposed within the chair and fastened securely to the inner sides thereof. The bearing-plate 12 comprises a body 12^a, flange 13, and securing means 14. The flange 90 13 is projected at about right angles to the body of the plate and is disposed when the several parts are assembled beneath the longitudinal flanges 5 of the chair 1. The securing means for the bearing-plate consist of 95 lugs forming extensions of the said plate and projected from the ends thereof and preferably centrally upon the said ends. The lugs 15 are adapted to be rearwardly bent to embrace the ends of the rail-chair and rigidly 100 hold the bearing-plate in position within the chair. The flange 13 is provided with notches

- 16, which are located with reference to the disposal of the notches 7 and 8 of the respective extensions 6 and flanges 5 of the fish-plates and rail-chair. Openings 17 are disposed upon the base of the chair, and the locking-pins 9 and the wedges 4 pass through these openings, after which the transverse pins 11 are placed in the openings 10 to hold the said elements in place.
- 10 In placing the several parts of the device in position the bearing-plate is first disposed within the chair and secured in place by the extension-lugs 14. The fish-plates 2 are next slid endwise within the chair, the flanges 5 entering the space between the bodies of the fish-plates and the extensions thereof. The rails may be then placed by an endwise movement between the fish-plates. The locking-wedges 3 and 4 are next introduced into the 20 notches upon the fish-plates and chair and the locking-pins disposed within the openings 10 of the wedge 3. The pins 9 are placed in position at the same time and are located in the manner described. The rails being 25 provided with notches in the usual manner are also locked together, since the pins 9 and locking-wedges 3 are adapted to extend through the notches disposed in the ends of the said rails and to constitute the above 30 locking means. It is desirable to have the notches in the rails of somewhat greater width than the width of the respective locking wedges and pins, so that extension of the rails may be permitted.
- 35 As shown in the drawings, the openings adjacent the lower ends of the wedges 3 and the pins 9 are circular and receive the semi-circular locking-pins 11. The locking-pins engage or are seated in grooves 17 upon the 40 under side of the rail-chair. The openings 11 are thus more firmly retained in their positions and are additionally prevented from

displacement by the vibration of the rolling-stock passing over the rails.

Having thus described the invention, what 45 is claimed as new is—

1. In a rail-joint, and in combination, a rail-chair having longitudinal flanges thereon, fish-plates having longitudinal extensions projected therefrom to overlap the flanges of 50 the rail-chair, notches provided upon said chair-flanges and extensions of the fish-plates, locking-wedges adapted to enter the notches of the fish-plates and pass through openings in the bottom thereof, means for locking said 55 wedges in place, a bearing-plate disposed within the rail-chair, and means whereby the said bearing-plate may be locked in position with the chair, substantially as described.

2. In a rail-joint, and in combination, rails, 60 a rail-chair provided with longitudinal flanges, fish-plates having longitudinal extensions projected therefrom to overlap the flanges of the rail-chair, notches provided upon the said extensions and the flanges of the rail-chair, 65 openings in the base of the rail-chair, locking wedges and pins adapted to pass transversely of the notches and openings in the rail-chair and fish-plates respectively, a bearing-plate disposed within the rail-chair and 70 provided with a longitudinal notched flange, lugs extending from the ends of the bearing-plate and adapted to be bent to embrace the ends of the rail-chair to secure the said plate to the rail-chair, the locking pins and wedges 75 being adapted to prevent longitudinal movement of the said bearing-plate, substantially as described.

In testimony whereof I affix my signature in presence of two witnesses.

JAMES BOOTH. [L. S.]
